UNITED STATES PATENT OFFICE.

CHARLES P. GARTEN, OF ASHLAND, KENTUCKY.

HINGED BOTTOM FOR DRY MEASURES.

1,217,588.

Specification of Letters Patent. Patented Feb. 27, 1917.

Application filed July 11, 1916. Serial No. 108,599.

To all whom it may concern:

Be it known that I, CHARLES P. GARTEN, a citizen of the United States, residing at Ashland, in the county of Boyd and State 5 of Kentucky, have invented certain new and useful Improvements in Hinged Bottoms for Dry Measures; and I do hereby declare the following to be a full, clear, and exact description of the invention, such as will enable others skilled in the art to which it 10 appertains to make and use the same, reference being had to the accompanying drawings, and to the letters and figures of reference marked thereon, which form a part of this 15 specification.

This invention relates to new and useful improvements in hinged bottom for dry measures for various purposes and consists of a simple and efficient device of this nature 20 having a hinged bottom with a releasing latch, affording means whereby, when it is desired to dispense the contents of the measure, it may be done by releasing the catch, allowing the bottom to swing down.

25 The invention comprises a simple and efficient apparatus of this nature having various details of construction, combinations and arrangements of parts which will be hereinafter fully described, shown in the accompanying drawings and then specifically defined in the appended claim.

I illustrate my invention in the accompanying drawings, in which:—

Figure 1 is a side elevation of a dry measure embodying the features of my invention, parts being broken away to better illustrate features.

Fig. 2 is a sectional view vertically through a measure and latch mechanism.

40 Reference now being had to the details of the drawings by letter, A designates a dry measure and B is a bottom hinged at C thereto. Said bottom is provided with a hook D at a point opposite its hinged portion and which hook extends approximately at right angles from the bottom and is adapted to engage an opening in the bottom of the boxing E upon the side of the measure. A latch, designated by letter H, is 45 pivotally mounted upon a pin I projecting from the wall of said boxing, and said latch is notched as at K for the reception of the free end of the hook D. The latch is also provided with a shoulder N against which 50 the inner end of a push rod O is adapted to

bear, said rod passing through an aperture R formed in the lip T which projects laterally from the upper portion of the measure on the outside thereof, the rod being provided with a head O'. A spring S is mounted 60 on said rod O and is interposed between the head O' and said lip. A coiled spring W bears intermediate the edge of the latch above its pivotal point and the wall of the boxing in which the latter is mounted and tends to normally hold the latch in a locking position 65 relative to the hook D.

It will be noted that, when the bottom closes, an inclined curved edge of the hook will come in contact with an inclined curved 70 end of the latch, thus causing the latter to tilt upon its pivot to allow the hook to pass by the same, after which the spring will throw the latch to its normal position.

The operation of my invention will be 75 readily understood and is as follows:—When it is desired to dispense or empty the contents of the measure, the operator merely pushes down upon the head O' of the rod O, causing the latch to tilt free from the hook, 80 after which the weight of the commodity within the measure will throw the bottom down and allow the contents to be dumped. When the door swings closed, it will be automatically locked, as will be readily understood. 85

What I claim to be new is:—

In combination with a receptacle, a boxing with an apertured top and slot in the bottom through which slot a hook is adapted to be passed, a latch pivoted to said boxing to the wall of the receptacle and having its lower free end hook and its upper end shouldered above its pivotal point and at one side of its longitudinal center, a spring 90 interposed between the upper portion of the latch and the wall of the boxing, said receptacle having an apertured projection near the top thereof, a spring-pressed rod mounted in said projection and an aperture in the 95 top of the boxing, the lower end of the rod bearing against the shouldered portion of the latch in alignment with the edge of the hook beneath.

In testimony whereof I hereunto affix my 105 signature in presence of two witnesses.

CHARLES P. GARTEN.
